APPARATUS FOR FEEDING SHEET MATERIALS

Joseph W. Young, Sutton, Mass., assignor to The Felters Company, Boston, Mass., a corporation of Massachusetts

Application August 3, 1950, Serial No. 177,391

4 Claims. (Cl. 270—62)

1

This invention relates to improved feeding apparatus for feeding a continuous web of sheet material wherein it may be desired, for example, to arrange the sheet material in folds to be passed between a series of rolls which squeeze the folds of material together.

In some continuous web handling operations as, for example, in the processing of certain felted materials, and other textile materials, it may be desirable to eliminate the use of aprons or carrier sheets to support and advance a folded web of material between one or more pairs of nip or squeeze rolls, both for the reason that the expense of the carrier aprons is avoided and for the further reason that the treatment of the web with fluids may be facilitated, if the aprons are not interposed between the pleated material and the squeeze rolls. Ordinarily if aprons are not employed and a pleated material folded upon itself in stepped relationship is passed through nip rolls, the stepped folds tend to stick or adhere to the peripheral surfaces of one or more of the nip rolls and the material becomes jammed or the pleated arrangement otherwise upset.

The present invention deals with the problem indicated and aims to provide an apparatus for feeding sheet material in folds between nip rolls without utilizing carrier aprons. It is also an object of the invention to provide a simple, efficient, and easily operated feeding apparatus for arranging and advancing pleated material between nip rolls. Still another object of the invention is to devise a novel means of arranging folds of sheet material occurring in the form of a continuous web whereby each of the folds is substantially enclosed within adjacent folds in a position such that it will resist adhering to either of the two opposed roll surfaces.

These and other objects and novel features will be more fully understood and appreciated from the following description of a preferred embodiment of the invention selected for purposes of illustration and shown in the accompanying drawings, in which

Fig. 1 is an end elevational view of the apparatus of the invention; and

Fig. 2 is a front elevational view.

Referring more in detail to the drawings, I have illustrated therein one desirable form of apparatus for carrying out the invention wherein a continuous web of sheet material, generally denoted by the letter M, is furnished from a roll 10 which is mounted for rotation with a horizontal shaft 12. The roll 10 may be mounted to rotate freely in response to tension exerted on

2

the material M or the roll may be geared to provide a positive power driven feed with suitable controls of well known character being utilized to vary the speed of rotation of the roll.

5 Numeral 14 indicates a folding device which preferably comprises a chute pivotally mounted on the same shaft 12 with roll 10 and constructed and arranged to provide an open upper end into which the sheet material M may pass as it leaves the roll periphery.

The chute is more clearly shown in Fig. 2 and may, in one suitable form, be provided with an eccentric driving mechanism consisting of a rotatably driven disk 16 and a link 18 connected 15 to one side of the chute to produce oscillatory movement of the latter member in the manner customary in eccentric devices of this nature.

In accordance with the invention I further combine with the folder chute 14, and furnishing roll, a series of oppositely rotating rolls which are located at points below the chute in a position to receive and support the sheet material as it leaves the lower end of the chute. These rolls may include, for example, two rolls 20 and 22 mounted to rotate in a clockwise direction, as shown in Fig. 1, and two additional rolls 24 and 26 mounted for rotation in a counter-clockwise direction, as shown in said figure.

The rolls 22 and 24 are spaced apart from one another a predetermined distance suitable for forming a guideway 26 and selected with reference to the thickness of the folded material which is to pass therebetween. Immediately below the rolls 22 and 24 is provided a conveyor belt 30 which may be driven by rollers 32, as shown in Fig. 1. The conveyor belt leads to a set of nip or squeeze rolls 34, 36, 38 and 40.

30 In making use of the apparatus described, the folder chute is caused to oscillate at a definite rate and material is then gravity fed from roll 10 through the chute and out of the lower end of this member to become folded in layers which are superimposed one above another, as has been diagrammatically shown in Fig. 1.

40 The swing of the folder chute may be selected of an amplitude such that each layer will extend across and above all four of the rolls 20, 22, 24 and 26, as illustrated, with the rolls 22, 24 and 26 rotating as explained above. The bottom layer of 50 folding material will be acted upon in such a way that outermost portions of the layer will be moved toward one another, as represented by the position of layer 40 in Fig. 1, and to a lesser extent by the position of the immediately overlying layer 55 42.

It will be apparent that the guideway 26 affords a passageway into which the doubled over portions of the layers may pass as these portions move by gravity in a downward direction. It will also be apparent that, by a suitable choice of guideway spacing, succeeding layers will be so folded that they will be caused to fit into one another in a nested relationship, which is better illustrated in that section of the folded material passing out of the guideway 26. By varying the width of the guideway the extent to which nesting takes place may be controlled to a considerable extent to thus provide an appreciable range of folding or pleating.

The nested material as it leaves the guideway 15 26 is received on the conveyor belt 38 and carried thereby to the squeeze rolls, as suggested at the left-hand side of Fig. 1. An important feature of the invention is the passage of the nested material through the rolls where the nested arrangement operates to present to the peripheral surfaces of the squeeze rolls or nip rolls, a series of overlapping sides, each of which sides is partially buried in the next succeeding fold so that there is no opportunity for any one of the sides to adhere to, or to be sucked around, a roll periphery and develop interference or jamming. On the contrary, each layer engages against, and draws with it, immediately succeeding layers.

It is pointed out that by means of this operation and the effect of the nested arrangement of the folds, there is eliminated the need for protecting aprons, with a consequent saving in equipment. It may also be desired to apply a treating liquid as, for example, from a liquid supply unit 50 arranged above the pleated material, as shown in Fig. 1. When this treating operation is combined with the squeeze roll action, it will be seen that a much faster and more efficient passage of the treating liquid through the folded material may be realized than would be the case if a protective apron were employed.

The speed of travel of the sheet material through the chute governs the load or number of pleats delivered in the nested position by the feeding device. For example, a speed of six yards of material per minute through the chute might deliver one yard per minute in the nested pleated condition. This ratio can vary up or down within the limits permitting travel of the treated mass through guideway 25 without clogging.

The travel speed of the delivered treated mass should preferably be synchronized through a subsequent set of rolls through which the mass might need to pass. The length of the throw or swing given by the holder arm has no relation to the amount of sheet material delivered, but it does govern the length of the pleat. In one illustrative example of the invention there has been employed a throw or swing having a travel of about thirty inches. Other dimensions, however,

may be employed in accordance with the conditions to be satisfied.

The apparatus has been exemplified in the drawings as folding a single continuous web. 5 However, it should be understood that a plurality of webs may be desired to be folded and fed in the same general manner described, for example, in forming felted materials, as in a multi-roller hat-making machine, or in various other machines for impregnating, scouring, dyeing, and the like, of fibrous sheet materials. It is also intended that the folding mechanism comprised by the oscillating chute may be varied, for example, by having a reciprocating chute member which travels across a series of folding rolls, rather than swinging about an axis.

These and various other changes and modifications may be resorted to in keeping with the invention as defined by the appended claims.

Having thus described my invention, what I desire to claim as new is:

1. An apparatus for feeding sheet material, comprising means for furnishing a continuous web of the sheet material, means for reversely 25 folding the material upon itself to form a series of superimposed layers, oppositely rotating rolls located below the chute in a position to receive the layers thereon and cause outermost portions of each bottom layer to move toward one another into doubled over relationship, said rolls being spaced apart to provide a guideway into which successive doubled over layers of material are advanced in nested relationship to one another, means for receiving the nested layers as 35 they leave the guideway, and a plurality of nip rolls arranged to engage opposite sides of the nested material during movement thereof.

2. A device as described in claim 1, in which the means for reversely folding the material comprises 40 a travelling folder chute.

3. A device as described in claim 2, in which the folder chute is pivotally mounted to swing about a horizontal axis.

4. A device according to claim 2, in which the 45 means for furnishing the sheet material consists of a roll of such material and the folder chute is provided with an open upper end constructed and arranged to receive material as it leaves the roll periphery and to guide the material along a vertically downward path.

JOSEPH W. YOUNG.
